UNITED STATES PATENT OFFICE.

WILLIAM McCALL, OF SAN FRANCISCO, CALIFORNIA, ASSIGNOR OF THREE-FOURTHS TO ELVIN C. McCALL, CLARENCE C. McCALL, AND MICHAEL O'SULLIVAN, OF SAME PLACE.

HINGED SLIDABLE WINDOW-SASH.

SPECIFICATION forming part of Letters Patent No. 591,356, dated October 5, 1897.

Application filed April 10, 1897. Serial No. 631,491. (No model.)

To all whom it may concern:

Be it known that I, WILLIAM McCALL, a citizen of the United States, residing in the city and county of San Francisco, State of California, have invented an Improvement in Hinged Slidable Window-Sashes; and I hereby declare the following to be a full, clear, and exact description of the same.

My invention relates to an improvement in windows and their sashes; and it consists, essentially, in combination, with the sashes, of independent vertical slides movable in guides in the casing and having window-weights connected with them, a novel means for locking the sashes to said sliding portions or to disengage them from the sashes and simultaneously lock the slides to the casing, and hinges upon the opposite edges of the sashes, whereby the latter may be opened inwardly while the weighted slides are retained in position by the locks.

It consists also in certain details of construction, which will be more fully described by reference to the accompanying drawings, in which—

Figure 1 is a view of a window, showing my improvements. Fig. 2 is a detail view of one of the sash-locks. Fig. 3 is an edge view of the same. Fig. 4 is a top view of the lower sash and connections. Fig. 5 is an enlarged cross-section of the strips M and L and a part of one of the slides. Fig. 6 illustrates a detail of the locking-bolts O and turnable sleeves P.

A is the window-casing, having the usual vertical guide-channels and sliding sashes and the weighted ropes to connect with the sashes and act as counterbalances to the latter when they are moved up and down.

C C are vertically-sliding strips interposed between the sashes and the casing, movable in the guides in the casing, and separated by the parting-strips thereof. One pair of these slides is fitted to the upper sash and the other to the lower sash. To each of these slides the cords B of the window-weights are attached, and the sashes D are hinged on one side to the slides on that side, as shown at E.

Upon the other side the sashes close 50 against shoulders H, formed upon the slides,

the sashes being correspondingly shouldered, as shown at H', so that when closed together the slides and the sashes are practically in line with each other.

In order to connect the sashes and the slides, I have shown the revoluble double-ended hooks pivoted in the slides at points near the top and bottom of each.

The hooks F have a common center or hub, about which they are turnable, one curved and projecting, so as to lock into the upper part of the sash, and the other correspondingly curved and projecting to lock into the lower part of the sash at one end, while the opposite ends are curved in the opposite directions, so that when desired they may be locked into the casing, while the first-named hooks are disengaged simultaneously from the sash. The object of these hooks is first to lock the slides and the sash together upon the side opposite the hinges of the sashes, and when they are thus locked together the two slides together as one structure.

When it is desired to open the sashes about their hinges, these locks are turned so as to disengage the hooks from the sashes and at the same time engage them with the casing, so that when the sashes are opened the slides will not be thrown up to the top by the action of the counterweights. This locking of the slides to the casing takes place when both sashes are brought down to the lowest point, so that one after the other may be opened inwardly for cleaning or other desired purpose without any change in position of either.

The hooks or latches are fulcrumed upon a hollow sleeve G, which projects through the plate in which it is fulcrumed and has a socket H² for the insertion of a suitable key by which to turn it.

I are spring-pressed latches which engage with notches J when the locking-hooks are turned so as to bring either of the notches opposite the latches—that is to say, when the latches are disengaged from the casing and are engaged with the sash they will be locked in that position by the catches, and when turned to engage the casing and be disengaged from the sash they are in like manner locked in that position. These latches are

mounted upon cam-plates I^2 , the lower edges of which are engaged by the arm g , and when it is turned it raises the cam-plate and the latch I . The hook F turns loosely on the short shaft to which the arm g is made fast. Now by turning this shaft the arm g will raise the cam-plate to which the spring-latch I is attached, and the latter will thus be lifted out of the notch J and will consequently release the hook F . The further movement of the arm g moves the pin g^2 , which is attached to it, to the end of the slot in the plate, in which this pin is movable. As soon as the pin reaches the end of the slot it begins to act upon the hook F and will move it until the latch I drops into the other notch J and again locks it. A further movement of the key engages the hook and turns it into the new position, where it is again locked by the falling of the catch into the notch at that side of the hook.

When the key is removed from the opening, the latches are secured in either position and cannot be accidentally turned.

Upon the hinge side the slides have fixed upon their faces which travel in the grooves in the casing metal strips L , so bent as to form hooks, as shown at l , and these extend behind and engage the metal strips M , which are secured in the bottom of the channels in the casing, these strips being raised at the edges and having sufficient space on each side to allow the hooks to engage them. By this means the strips on the hinge sides are secured, and while easily slidable vertically they will be prevented from being bodily withdrawn from the grooves or channels when the sashes are opened.

The slides upon the hinge side of the sashes are also provided with transversely-movable locking-bolts O , which are toothed or otherwise constructed to be engaged by the cylindrical turnable sleeves P , these latter being operated by keys in the same manner as those previously described upon the opposite side, so that when the windows are closed these bolts may be caused to engage the casing and thus prevent their being moved.

When it is desired to move the sashes, they may be disengaged by withdrawing the latches.

The operation of my device will then be as follows: When the sashes are in their normally-closed position, the hooks are turned so as to engage with the sashes and lock the sashes and the slides permanently together, the latches holding them, as previously described. When it is desired to open the sashes for any purpose, the lower sash is pushed up and the upper sash is pulled down to the bottom. When in this position, the key is first inserted to disengage the upper sash from its slide, and simultaneously with the turning of the latches to disengage the upper sash the slide is engaged with the opening in the casing and thus locked thereto, so that it cannot be pulled up by the ac-

tion of the counterweight. The lower sash is then pulled down to the bottom and in the same way disengaged from its slide, which is also locked to the casing to prevent the counterweight from pulling it up. The two sashes may then be opened about their hinges, both at the same time and upon the same level. In order to prevent their being moved up while in this condition, the lock O , previously described, may be turned to engage slots in the casing, thus locking the whole firmly in place. When the sashes are again closed and locked to the slides, the latter being at the same time disengaged from the casing, they will be in condition to be moved up and down in the usual manner.

Having thus described my invention, what I claim as new, and desire to secure by Letters Patent, is—

1. The combination with window-sashes of slides adapted to travel vertically in grooves in the casing with connected counter-balance-weights, hinges by which the sashes are connected to the slides upon one side and about which the sashes are turnable, a turnable sleeve having latches adapted to engage with the sashes when the latter are closed upon the slides, and to be disengaged therefrom and engaged with the openings in the casing whereby the slides are locked and prevented from being moved by the counter-weights when the sashes are opened therefrom and a means engaging the latches and holding them in a locked position.

2. The combination with window-sashes of slides movable vertically in grooves in the casing, hinges by which one edge of each sash is connected with a corresponding slide, pivoted double-ended latches within the slide upon the opposite side, openings in the edges of the sash adapted to be engaged by the latches upon one side whereby the sash and slide are connected together, corresponding openings in the casing adapted to be engaged by the latches upon the opposite side of the slides simultaneously with their disengagement from the sashes, whereby the latter are allowed to swing about their hinges while their slides are locked to the casing, a means engaging the latches in their several positions and holding them in a locked condition and means for releasing said latches.

3. The combination with window-sashes of a pair of slides for each sash adapted to move in grooves or channels in the casing, hinges by which one edge of a sash is connected with one of said slides, double-ended latches pivoted in the casing upon the opposite side, holes or depressions in the sash and in the casing whereby the latches are engaged with the sash and disengaged from the casing or engaged with the casing and disengaged from the sash simultaneously and spring-pressed catches adapted to engage and lock the latches in either position.

4. A window-sash and slides, to one of which the sash is hinged and to the other of which

it is connected or disconnected by turnable latches, double-ended latches mounted upon a central turnable sleeve, having one end adapted to enter and engage a slot by which the slide is temporarily locked to the sash and the other end to engage and lock the slide to a corresponding slot in the casing and simultaneously disengage it from the sash, spring-pressed latches, a sleeve upon which the turnable latches are mounted having an opening to receive a key by which the sleeve is turnable from the outside and an arm turnable with the sleeve whereby the spring-catches are first disengaged from the turnable latches and the latter are afterward turned to engage either with the sash or casing.

5. In a window and sashes of the class described, the independent slides movable in vertical guides in the casing, hinges by which the sashes are connected to the slide upon one side, and latches by which the opposite edge of the sash is engaged with or disengaged from the slide upon that side, said catches operating to simultaneously engage

the slide with the casing when it is disengaged from the sash, locking devices upon the slide to which the sash is hinged, whereby said slide and sash are temporarily locked to the casing and means for releasing the locking devices.

6. In a window with slideable sashes of the class described independent slides movable in guiding-channels in the casing, hinges by which the sash is engaged with the slide upon one side, a guide-strip fixed in the casing and a hook-slide fixed to the edge of the sliding strip to which the sash is hinged, with its edges turned over to engage the strip in the casing whereby the slide is kept in position and prevented from falling outwardly when the sash is opened.

7. In witness whereof I have hereunto set my hand.

WILLIAM McCALL.
